UNITED STATES PATENT OFFICE.

JOSEPH LEDWINKA, OF PHILADELPHIA, PENNSYLVANIA, ASSIGNOR TO EDWARD G. BUDD MANUFACTURING COMPANY, OF PHILADELPHIA, PENNSYLVANIA, A CORPORATION OF PENNSYLVANIA.

DESIGN FOR AN AUTOMOBILE FENDER.

Application filed November 14, 1925. Serial No. 15,419. Term of patent 14 years.

To all whom it may concern:

Be it known that I, JOSEPH LEDWINKA, a citizen of the United States, residing at Philadelphia, in the county of Philadelphia and State of Pennsylvania, have invented a new, original, and ornamental Design for Automobile Fenders, of which the following is a specification, reference being had to the accompanying drawing, forming part thereof, wherein—

Figure 1 is a perspective view of an automobile fender, showing my new design and Figure 2 is a top plan view thereof.

I claim:

The ornamental design for an automobile fender, as shown.

Signed at Philadelphia, in the county of Philadelphia, in the State of Pennsylvania, this 13th day of November, 1925.

JOSEPH LEDWINKA.
